(57) **CLAIM**

The ornamental design for tool handles, as shown and described.

DESCRIPTION

FIG. 1 is a front/side/top isometric view of the tool handles; FIG. 2 is a front elevational view of one of the tool handles, the front elevational view of the other handle being a reverse image of that shown;

FIG. 3 is a rear elevational view of one of the tool handles, the rear elevational view of the other handle being a reverse image of that shown;

FIG. 4 is a right side elevational view of one of the tool handles, the left side elevational view of the other handle being the same as that shown;

FIG. 5 is a left side elevational view of one of the tool handles, the right side elevational view of the other handle being the same as that shown;

FIG. 6 is a top plan view of one of the tool handles, the top plan view of the other handle being a reverse image of that shown; and,

FIG. 7 is a bottom plan view of one of the tool handles, the bottom plan view of the other handle being a reverse image of that shown.

The broken lines immediately adjacent the shaded areas represent the bounds of the claim and all other broken lines are for illustrative purposes only. None of the broken lines forms a part of the claimed design.
